CLAIM

The ornamental design for an oral-therapy tool, substantially as shown and described.

DESCRIPTION

FIG. 1 is a front right perspective view of an oral-therapy tool in accordance with our new design;

FIG. 2 is a back left perspective view of the oral-therapy tool of FIG. 1;

FIG. 3 is a right side elevation view of the oral-therapy tool of FIG. 1;

FIG. 4 is a left side elevation view of the oral-therapy tool of FIG. 1;

FIG. 5 is a top plan view of the oral-therapy tool of FIG. 1; FIG. 6 is a bottom plan view of the oral-therapy tool of FIG. 1;

FIG. 7 is a front side elevation view of the oral-therapy tool of FIG. 1; and,

FIG. 8 is a back side elevation view of the oral-therapy tool of FIG. 1.

The threaded portion in the various figures, shown in dashed lines, forms no part of the claimed design.

1 Claim, 4 Drawing Sheets
